PISTON FOR ENGINES

Filed April 7, 1922

Rolland S. Trotter INVENTOR.

UNITED STATES PATENT OFFICE.

ROLLAND S. TROTT, OF DENVER, COLORADO.

PISTON FOR ENGINES.

Application filed April 7, 1922. Serial No. 550,345.

To all whom it may concern:

Be it known that I, ROLLAND S. TROTT, a citizen of the United States, residing at Denver, county of Denver, and State of Colorado, have invented certain new and useful Improvements in Pistons for Engines, of which the following is a specification.

- The object of my invention is to provide a flexible skirted piston which will be an improvement over the latest piston invented by my friend and associate, Mr. Charlie E. Hatch, the serial number of his patent application being 538,906, and the date of filing February 24th, 1922.
- 15 A further object is to provide in a flexible skirted piston having all the practical advantages of the above named piston, a construction which will be better adapted to the die-casting process used in large production of aluminum alloy pistons.

In the Hatch piston the wrist pin lugs depend from the head portion and are entirely separate from the skirt portion.

This produces a flexibility which, at least 25 at some points, is much greater than is actually necessary, and which naturally reduces the strength of the piston.

In my piston, the wrist pin lugs on the side that takes the thrust of the connecting 30 rod on the power stroke, are attached to the skirt to within a short distance of the lower extremity of the lugs.

In the Hatch piston, the portion of the skirt directly below the center of the wrist 35 pin is the weakest and hence the most flexible part of the skirt, so that it seems to me that at this point most of the very slight movement that occurs in any case, will take place.

40 If this is true, then connecting one side of the lug to the skirt, while greatly strengthening the piston, detracts but little from its flexibility. So that this construction should be practically as flexible and much stronger 45 than the Hatch construction. And, by providing more relief, over a wider area adjacent to the extremities of the wrist pin bore, any danger of scoring at these points will be overcome.

50 As in the Hatch piston, one side of the skirt is split by a single, slightly diagonal, longitudinal cut, connecting with a transverse cut which joins the apertures adjacent to the wrist pin lugs.

55 In the Hatch piston, a post, separate from

the walls of the head portion, connects the skirt on either side of the longitudinal cut with the piston head.

This has worked out beautifully in practice, but it is very difficult to cast properly, especially by the die-casting process, where the metal cores must be removed from between these posts and the wall of the head portion of the piston.

We have also noticed that when the steel expansion ring is in place in the Hatch piston, the longitudinal cut is tapered, being considerably wider at the lower extremity of the piston, which indicates that each post with its connected skirt part acts as a hinge 65 swinging about the junction point of the post with the piston head. So, there is much less movement just below the transverse cut than there is at the lower extremity of the skirt. This is shown by the taper of the cut 70 as stated above.

But, the movement just below the transverse cut has proven to be ample for any condition, so the greater possible movement 75 at the lower extremity of the skirt is much more than is necessary.

In other words, our experiments have shown us that though very little movement is required, a certain small amount is positively necessary over the entire surface of the skirt which touches the cylinder wall; that is, any rigid point touching the cylinder 80 wall must have a flexible point directly opposite it.

In other words, if, as in my piston, less 85 than 180° of the skirt which touches the cylinder wall is rigidly attached to the wrist pin lugs, there can be no scoring provided the remainder of the 360° of the skirt has a slight amount of flexibility over its entire surface from the transverse cut to the lower extremity of the skirt.

Hence, I see no reason for providing any part of the skirt with the excessive and unnecessary flexibility of the lower extremity 90 of the skirt of the Hatch piston.

That is, if the entire surface of the skirt has no more flexibility than that portion of the Hatch piston just below the transverse cut, the results should be as good as if a greater, but un-used flexibility were provided.

For, the skirt does not have to expand even so much as a Sixteenth of an inch; a matter 95 of a few thousandths is all that is required,

or possible; but that few thousandths must positively be provided over the entire skirt surface for more than 180° in extent.

So, a flexibility no greater than the minimum obtained in the Hatch piston skirt is all that I desire to provide, but I desire that much for the entire surface of the skirt for more than 180° .

Hence, instead of connecting the skirt on either side of the longitudinal cut with the piston head by posts, I connect it to the rigidly supported wrist pin lugs by ribs designed to provide the amount of flexibility desired. In other words, I use the wrist pin lugs and their supports to take the place of the posts in the Hatch piston.

In the drawings, Figure 1 is a side elevation of my piston looking at right angles to the wrist pin bore; Figure 2 is a side elevation in partial section, taken at right angles to Figure 1; Figure 3 is an end elevation of the piston showing a modified form of the ribs connected to the wrist pin lugs and supporting the skirt adjacent the longitudinal cut; and Figure 4 is a horizontal sectional view taken on the line of the wrist pin bore and the line X—X of Figure 1.

The wrist pin lugs 1 are rigidly attached to the head 1^a by the external ribs 2, and the internal ribs 3, and are separated from the skirt 4 by the apertures 4^a, which extend up to the head portion on one side of the lugs, but only a fraction of that distance on the other side of the lugs. Either two or three ribs may be used to support each wrist pin lug in place of the single rib 3 shown, if desired, just so the construction in any case is strong enough so that no breakage will ever be possible.

The skirt 4 is provided on the side which has the high apertures 4^a, with the single, slightly diagonal, longitudinal cut 5, connecting at its upper end with the transverse cut 6.

The transverse cut 6 connects at its ends with the apertures 4^a, adjacent the wrist pin lugs 1. The wrist pin lugs 1 may be used as bearings, bushed if desired, and the wrist pin may be clamped in the connecting rod instead of locked in the wrist pin lugs as shown; the essentials of the piston being the same in either case.

The expanding ring 7 fits in the internal ring groove in the skirt 4 below the apertures 4^a. The slightly thicker portion forming the internal ring 8 at the lower extremity of the skirt is provided to facilitate finishing the piston.

The ribs 9 connect the skirt on either side of the cut 5 with the lugs 1. These ribs 9 may be varied in shape and dimensions, and also in length as well as in the points of their attachment with both the skirt and the lugs, so that it can be seen that a wide range of flexibility of the skirt may be obtained

by proper variation in the design of these ribs 9.

If desired, the rib 2^a, joining the lugs 1 on the side opposite the cut 5 may be employed to stiffen the lugs against movement due to the connection with the skirt through the ribs 9.

The portion of the piston above the transverse cut 6 is to be given enough clearance with the cylinder wall so that it can never touch the cylinder wall under any condition of operation.

The outer surface of the piston on either side of the wrist pin lugs for a distance, and from the height of the transverse cut 6 to the lower extremity of the skirt is relieved so that it can never touch the cylinder walls. The exact dimensions of this relieved area will depend upon the size of the piston, its material, and the duty it has to perform, as well as the conditions under which it must operate.

Considered in a longitudinal direction, the ribs 9 space the skirt of the piston some distance from the point of rigid support, so that there is no point of the skirt supported by the ribs 9 that is contiguous to a rigid section that touches the cylinder walls.

Considered in a circular direction, the relieved areas adjacent the extremities of the wrist pin bore precludes any part of the flexible portion of the skirt from being contiguous to a rigid section thereof.

It can now be seen that this piston is much stronger than the Hatch piston, that the position of the ribs 9 make it much easier to withdraw the metal cores in the die-casting process; that practically equal flexibility over the entire surface of the cut side that bears against the cylinder wall is obtained; and that the amount of flexibility may be varied as desired by proper design and dimensions.

Having now described my invention, what I claim as new, and desire to protect by Letters Patent, is as follows:—

1. A piston composed of a head section provided with a plurality of piston ring grooves and with wrist pin lugs rigidly integral therewith, a skirt section attached directly to said head section upon but one side of a center line, and directly to said wrist pin lugs for but a part of their adjacent sides, and provided with a single longitudinal cut on the other side of said center line, and with flexible means on either side of said cut joining said skirt to said lugs.

2. A piston composed of a head section provided with a plurality of piston ring grooves and with wrist pin lugs rigidly integral therewith, a skirt section composed of two faces adapted to contact with the cylinder wall with the intermediate portions relieved, one of said faces being directly at-

- tached to said head section and to part of said wrist pin lugs, the other face being separate from said head section and said lugs and provided with a single longitudinal cut 5 and with flexible means on either side of said cut connecting said face directly to said lugs.
3. A piston composed of a head section provided with wrist pin lugs rigidly integral therewith, a skirt section depending from said head section and separated from said wrist pin lugs by apertures for a part of their periphery and provided with a solid thrust face and a flexible thrust face, the 15 portions separating these two faces being relieved so as not to touch the cylinder wall, the flexible thrust face being provided with a single longitudinal cut and with a transverse cut in connection therewith and connecting with said apertures, and flexible means connecting the flexible thrust face with said lugs.
4. A piston composed of a head section with wrist pin lugs integral therewith, a 25 skirt section depending from said head section and attached thereto at only part of its periphery, and provided opposite said part with a longitudinal cut and flexible means on either side of said cut connecting 30 said skirt to said lugs.
5. A piston composed of a head section with wrist pin lugs integral therewith, a skirt section depending from said head section and separated therefrom for more than 35 180° in circular extent, said separated part and said connected part being joined by relieved portions, said separated part being provided with a longitudinal cut therethrough and with flexible means connecting 40 it with said lugs.
6. A piston composed of a head section
- with wrist pin lugs integral therewith, a skirt section depending from said head section and attached thereto at only part of its periphery, and provided opposite said part 45 with a longitudinal cut, flexible means on either side of said cut connecting said skirt to said lugs, and expanding means within said skirt section.
7. A piston composed of a head section 50 with wrist pin lugs integral therewith, a skirt section depending from said head section and attached thereto at only part of its periphery, and provided opposite said part 55 with a longitudinal cut, flexible means on either side of said cut connecting said skirt to said lugs, an internal ring groove within said skirt and expanding means within said groove.
8. A piston composed of a head section 60 with wrist pin lugs, a skirt section composed of two faces joined by relieved portions, one of said faces extending for less than 180° and attached direct to said head section and to a portion of said lugs, the 65 other of said faces having no direct connection with said head section or said lugs, and provided with a single longitudinal cut and with flexible means connecting with said lugs.
9. A piston composed of a head section 70 with wrist pin lugs, a skirt section composed of two faces joined by relieved portions, one of said faces extending for less than 180° and attached direct to said head section and to a portion of said lugs, the other of said faces having no direct connection with said head section or said lugs, and provided with a single longitudinal cut and with flexible 75 means connecting with said lugs, and expanding means within said skirt section.

ROLLAND S. TROTT.
